US0D1061894S

(12) **United States Design Patent** (10) **Patent No.:** **US D1,061,894 S**
(45) **Date of Patent:** **** Feb. 11, 2025**

(54) **MEDICAL DEVICE**

(71) Applicant: **i-Lumen Scientific, Inc.**, Bloomington, MN (US)

(72) Inventors: **Marshall T. Masko**, Minnetonka, MN (US); **John C. Velure**, Minnetonka, MN (US); **Thu-Ha Duncan**, Cleveland, TN (US); **Alexander B. Lemaire**, Edina, MN (US); **Charles A. Lemaire**, Apple Valley, MN (US)

(73) Assignee: **i-Lumen Scientific, Inc.**, Bloomington, MN (US)

(**) Term: **15 Years**

(21) Appl. No.: **29/754,410**

(22) Filed: **Oct. 9, 2020**

(51) LOC (15) Cl. **24-03**

(52) U.S. Cl.

USPC **D24/155**

(57) **CLAIM**

The ornamental design for a medical device, as shown and described.

DESCRIPTION

This application is related to:

U.S. Pat. No. 10,391,312, issued Aug. 27, 2019 to Blair P. Mowery et al. and titled “Apparatus and Method for Ocular Microcurrent Stimulation Therapy”;

U.S. Provisional Patent Application No. 62/283,870, filed Sep. 15, 2015 by Mowery et al., titled “Appliance for Microcurrent Stimulation Therapy Using a Disposable Material Afixed to the Upper and Lower Eye Lid & Other Body Parts”;

U.S. Provisional Patent Application No. 62/283,871, filed Sep. 15, 2015 by Masko et al., titled “Apparatus for a Method of Application of Microcurrent Stimulation Therapy, Consisting of a Google Device Affixed to & Encircling the Upper and/or Lower Eyelids, as Well as Other Body Parts”;

U.S. Provisional Patent Application No. 62/365,838, filed Jul. 22, 2016 by Tapp et al., titled “Appliance for micro-current stimulation”;

U.S. Provisional Patent Application No. 62/783,116 filed on Dec. 20, 2018, by Masko et al., titled “Apparatus for a Method of Application of Microcurrent Stimulation Therapy”;

U.S. Provisional Patent Application No. 63/025,987, filed May 15, 2020, by Duncan et al., titled “Electrode System for Vision Treatment and Method”; each of which is incorporated herein by reference in its entirety.

FIG. 1 is a perspective view of the decorative medical device showing the new design;

FIG. 2 is a top view thereof;

FIG. 3 is a bottom view thereof;

FIG. 4 is a left-side view thereof;

FIG. 5 is a right-side view thereof;

FIG. 6 is a front view thereof; and,

FIG. 7 is a back view thereof.

In FIGS. 1-7, the broken lines are for the purpose of illustrating portions of the earpiece that are not part of the claimed design.

1 Claim, 6 Drawing Sheets
